MULTIPOST LIFT

Ion Von Kert Hott, Dayton, Ohio, assignor to The Joyce-Cridland Company, Dayton, Ohio, a corporation of Ohio

Application August 15, 1935, Serial No. 36,376

10 Claims. (Cl. 254—93)

This invention relates to a multi-post lift and is designed primarily for elevating motor driven vehicles to permit access to be had to the underneath parts thereof for servicing. When the vehicle is located off center on a multi-post lift or when the vehicle is of greater weight at one end than at the other the load is unequally distributed between the lifting elements and that lifting element having the lighter load will move a greater distance than the lifting element having the heavier load which results in the tilting of the load supporting structure. If unrestrained the tilting of the load support will continue until it has reached an inclination which is dangerous.

One object of the present invention is to provide a fluid operated multi-post lift in which the delivery of fluid to the lifting elements will be automatically controlled to cause these lifting elements to move substantially equal distances, thereby preventing any considerable tilting of the load supporting structure.

A further object of the invention is to provide such a lift in which the flow of fluid to the lifting elements will be directly controlled by the initial tilting of the load supporting structure.

A further object of the invention is to provide such a lift in which the exhaust of the fluid from the cylinders will also be controlled so that the load supporting structure will be held against substantial tilting movement during the lowering of the load as well as during the raising of the load.

A further object of the invention is to provide such a lift in which the controlling mechanism will be simple in construction and operation and will positively control the relative movements of the lifting elements.

A further object of the invention is to provide such a lift with a controlling mechanism of the character above mentioned which can be easily installed on existing lifts without substantial modification thereof.

Other objects of the invention may appear as the mechanism is described in detail.

In the accompanying drawings Fig. 1 is a side elevation of a multi-post lift embodying my invention, with the lower portions of the cylinders broken away; Fig. 2 is a transverse section taken on the line 2—2 of Fig. 1; Fig. 3 is a transverse section taken on the line 3—3 of Fig. 1; Fig. 4 is a side elevation of the controlling mechanism, partly in section; Fig. 5 is a diagrammatic illustration showing the several conduits and their controlling valves; Fig. 6 is a horizontal section taken on the line 6—6 of Fig. 4; Fig. 7 is a trans-

verse section taken on the line 7—7 of Fig. 6; Fig. 8 is a transverse section taken on the line 8—8 of Fig. 6; Fig. 9 is a transverse section taken on the line 9—9 of Fig. 6; Fig. 10 is a transverse section taken on the line 10—10 of Fig. 6; Fig. 11 is a longitudinal section taken on the line 11—11 of Fig. 6; Fig. 12 is a longitudinal section taken on the line 12—12 of Fig. 6; and Fig. 13 is a longitudinal section taken on the line 13—13 of Fig. 6.

In these drawings I have illustrated one embodiment of my invention and have shown the same as applied to a two post fluid operated lift, that is, a lift having a single lifting element at each end thereof. I have also shown the cylinders of the lifting elements as sunk in the ground but it will be understood that this particular embodiment has been chosen for the purpose of illustration only and that the invention may take various forms and may be applied to fluid operated lifts of various kinds having two or more lifting elements.

In that embodiment of the invention here illustrated the lift comprises two posts or lifting elements 15 and 16 each of which comprises a vertical cylinder 17 which, in the present instance, is sunk in the ground, and a ram 18 mounted for longitudinal movement in the cylinder. A load supporting structure of any suitable character is secured to the upper ends of the rams 18, preferably in such a manner that it may have tilting movement with relation thereto. The particular lift here shown is of the free wheel type and the load supporting structure comprises a pair of parallel rails 19 supported near their ends on the respective rams 18. The rails are here shown as H-beams and are thus provided with channels on the inner sides thereof, and plates are mounted in the channels of the respective rails adjacent to each ram. The plates 20, adjacent to the lifting element 16, are rigidly secured to the rails, as by welding, and are provided with bearings 21, here shown as inwardly extending bosses. Rigidly secured to the upper end of the ram of the lifting element 16 is a cross member 22 having parts, such as the ends of a shaft 23, rotatably mounted in the bearings 21. Mounted in the channels of the rails 19 adjacent to the lifting element 15 are plates 24 which are slidable lengthwise of the rails and are here shown as mounted in guideways formed between the vertical webs of the rails and projections 25 spaced from said web. These plates are also provided with bearings, as shown at 26, and a cross member 27 is rigidly secured to the 55

adjacent ram and provided with parts, such as the ends of a shaft 28, rotatably mounted in the bearings. Thus the load supporting structure is movable at one end about a fixed axis and at its other end about an axis which is movable lengthwise thereof to compensate for the increased distance between the upper ends of the rams when the latter are at different heights.

Connected with the cylinders of the respective lifting elements are conduits 29 and 30 which are adapted to be connected with a suitable source of supply for fluid under pressure, such as a reservoir 31 adapted to contain oil under air pressure, air under pressure being delivered to the reservoir through a pipe 32 and exhausted therefrom through a pipe 33, and the two pipes being controlled by separate valves 34 in a well known manner. A pipe 35 leads from the reservoir 31 and is connected with the conduits 29 and 30 through suitable controlling mechanism and is also provided with a cut-off valve 36.

The controlling mechanism comprises valves interposed between the reservoir pipe 35 and the conduits 29 and 30 and adapted to be controlled in accordance with the angular position of the load supporting structure 19 so that a slight initial tilting of the load supporting structure will reduce the flow of fluid to the higher ram and thus retard its movement and prevent the further tilting of the load supporting structure. Referring first to the diagrammatic illustration of Fig. 5 it will be noted that the conduit 29, which is connected with the lifting element 16, comprises two branches 37 and 38 and that the conduit 30 which is connected with the lifting element 15 also comprises two branches 40 and 41. The branch 37 of conduit 29 is connected at that end remote from its lifting element with a main conduit 42 which is connected with the reservoir pipe 35. Mounted in this conduit is a valve 43 which is normally open to permit the flow of fluid therethrough and which is provided with an actuating device, such as the valve stem 44. Interposed in the conduit 37, between the valve 43 and the main conduit 42, is a check valve 45 arranged to permit fluid to flow from the main conduit to the valve but to prevent fluid from flowing from the valve 43 back to the main conduit. The branch 38 of conduit 29 extends beyond the branch 37 and is connected with the main conduit 42. A check valve 46 in the conduit 38 permits the flow of fluid from the conduit 29 to the main conduit but prevents the flow of fluid from the main conduit to the conduit 29. The flow of fluid through the conduit 38 is controlled by a valve 47 having an actuating device or stem 48, this valve also being normally open. The branch 40 of conduit 30 is connected with the main conduit 42 and is provided with a normally open controlling valve 49, having an actuating device or stem 50, and with a check valve 51 to prevent fluid from flowing from the conduit 30 to the main conduit. The branch 41 of the conduit 30 extends to a point adjacent to the inner end of the conduit 37 and is connected with the main conduit 42 and is also provided with a check valve 52 to prevent fluid from flowing from the main conduit to the conduit 30 and with a normally open controlling valve 53 having an actuating device 54. During the elevation of the load fluid under pressure flows through the reservoir pipe 35, main conduit 42 and through the branch conduits 37 and 40 to the conduits 29 and 30 which are connected respectively with the

cylinders of lifting elements 16 and 15. The valves 43 and 49 are normally open so that fluid flows in substantially equal quantities to the two lifting elements and when these lifting elements carry substantially equal loads they will move upwardly in unison and the load supporting structure will remain substantially horizontal, or if, as in some cases, it is normally supported at a slight inclination it will be retained at the predetermined angle. When the load is being lowered the fluid will flow from the cylinders, under pressure of the load, through conduits 29 and 30 and branches 38 and 41 to the main conduit 42 and thence back to the reservoir. The valves 47 and 53 are likewise normally open and when the lifting elements are equally loaded they will move downwardly in unison.

In order to cause the lifting elements to move at substantially the same speed and thus move substantially the same distances, thereby maintaining the load supporting structure in its horizontal position, I have provided means for automatically actuating the controlling valves in the several branch conduits. This means is of such a character that when, during the elevation of the load, the load supporting structure is tilted the controlling valve in the branch conduit leading to the lifting element supporting the higher end of the load supporting structure will be closed or partially closed to restrict the supply of fluid to that lifting element, thereby retarding the movement of that end of the load supporting structure and preventing the further tilting thereof. The restriction of the flow of fluid to one lifting element will permit a greater flow of fluid to the other lifting element, thus providing the latter with additional power to lift the heavier load thereon. If, during the lowering of the load, the supporting structure tilts the valve in the branch conduit leading to the lifting element which supports the lower end of the load supporting structure will be closed or partly closed to restrict the escape of fluid from that lifting element and thus retard its downward movement.

The means for actuating these valves may take various forms but it preferably comprises an actuating member 55, here shown in the form of a tubular rod, which is so connected with the load supporting structure that it will be moved by the tilting movement of that structure. Preferably it is rigidly secured to the load supporting structure so that it will move with and will be tilted simultaneously with the tilting of the load supporting structure. In the present instance, the actuating device 55 is provided at its upper end with a transverse head 56 which is pivotally connected at 57 with a supporting member 58 which is rigidly but adjustably secured to and extends laterally from the cross member 22 which connects the rails to lifting element 16. Screws 59 which are threaded in the supporting member 58 engage the head 56 on opposite sides of its axis so as to establish a rigid connection between the actuating rod 55 and the load supporting structure, but the adjustment of the screws will enable the rod to be positioned at different angles with relation to the load supporting structure, as, for example, when the latter is normally supported at an angle. The actuating member 55 extends downwardly into such relation to the valve actuating devices that its movement in one direction will operate the supply valve for the conduit leading to one lifting element and the exhaust valve in the conduit leading from the other lifting element. While both valves are operated only one

valve is effective because the check valves prevent the flow of fluid through the exhaust branch during the lifting of the load and through the supply branch during the lowering of the load. In the present apparatus the controlling valves are arranged in pairs, the supply valve 43 and the exhaust valve 53 being arranged on one side of the actuating member 55 and the supply valve 49 and the exhaust valve 47 being arranged on the other side of the actuating member. The actuating devices for the valves of each pair are connected one to the other by cross members 60 which lie close to and may, if desired, contact with the respective sides of the actuating member. Hence any tilting of the load supporting structure will also tilt the actuating member and move the latter in a direction to close or partly close the supply valve leading to the lifting element supporting the higher end of the load supporting structure, if the load is being elevated, or, if the load is being lowered, to close or partly close the exhaust valve leading from the lifting element which supports the lower end of the load supporting structure.

Referring now to the detail drawings illustrating the conduits and their valves, Figs. 6 to 13, it will be observed that these parts are formed in a unitary structure having at its respective ends parts 61 and 62 with which the conduits 29 and 30 are connected, these parts being herein referred to as valve casings. The several parts of the unitary structure may be rigidly connected one with the other in any suitable manner, as by casting the same in one piece. The supply branch for each conduit, 29 and 30, and its valve, are in the valve casing with which the conduit is connected, and the exhaust branch for each of said conduits extends to the valve casing with which the other conduit is connected and has its valve in that valve casing. In the arrangement here illustrated the main conduit 42 is connected at its ends with the respective valve casings and is connected between its ends with the reservoir pipe 35. The supply branch conduit 37, which connects the main conduit 42 with the conduit 29 is formed in the valve casing 61, (see Figs. 6, 9, and 10) and comprises a transverse passageway 63 leading from the main conduit 42 to a valve chamber 64 in which the supply valve 43 is mounted. This valve chamber 64 is connected by a port 65 with a passageway 66 leading to the conduit 29. Likewise the branch 40 which connects the main conduit 42 with the conduit 30 is formed in the valve casing 62, (Figs. 6, 7, and 8) and comprises a transverse passageway 67 which leads from the main conduit 42 to a valve chamber 68 in which the supply valve 49 is mounted and this valve chamber is connected by a port 69 with a passageway 70 leading to the conduit 30. The supply valves 43 and 49 are held normally in their open positions by springs 91 and the check valves 51 and 52 are interposed between the respective transverse passageways 67 and 63 and the main conduit 42.

The return or exhaust conduit 38 which connects the conduit 29 with the main conduit 42 comprises a transverse passageway 71, in valve casing 61, (Figs. 9 and 10), which is connected with the passageway 66 leading to the conduit 29 and this transverse passageway is connected by the longitudinal portion of the branch with a second transverse passageway 72, in valve casing 62, (Figs. 6 and 7), which leads to a valve chamber 73 in which the exhaust valve 47 is mounted, and this valve chamber is connected by a port 74

(Fig. 8) with transverse passageway 75 extending above the valve chamber 68 and connected through the check valve 46 with the main conduit 42. The return or exhaust branch 41 which connects the conduit 30 with the main conduit 42 comprises a transverse passageway 76, in valve casing 62, (Figs. 7 and 8), which is connected at one end with the passageway 70 leading to the conduit 30 and is connected by the longitudinal portion of the branch with a transverse conduit 77, in valve casing 61, (Figs. 6 and 9), which leads to a valve chamber 78 in which the exhaust valve 53 is mounted and this valve chamber 78 is connected by a port 79 (Fig. 10) with a transverse passageway 80 leading through the check valve 45 to the main conduit 42. The exhaust valves 47 and 53 are held normally in their open positions by springs 81.

The structure which includes the controlling valves and their conduits may be arranged in any suitable position below the load supporting structure and preferably it is enclosed within a housing 82 which is sunk in the ground adjacent to one of the lifting elements and the actuating member 55 is so mounted on the load supporting structure that it will extend through the housing between the two pairs of valve actuating members, an opening 83 being provided in the ground beneath the housing to receive the lower portion of the actuating member.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In a multi-post lift comprising a plurality of fluid operated elements and a load supporting structure carried by said lifting elements and capable of tilting movement with relation thereto, means for connecting the respective lifting elements with a source of fluid supply, each connecting means comprising a valve to control the flow of fluid to its lifting element and a second valve to control the return of the fluid from its lifting element to said source of supply, and means controlled by the tilting movement of said load supporting structure in one direction to actuate the supply valve for one lifting element and the exhaust valve for another lifting element.

2. In a multi-post lift comprising a plurality of fluid operated lifting elements and a load supporting structure carried by said lifting elements, and capable of tilting movement with relation thereto, an actuating member rigidly connected with said load supporting structure and operable by the tilting movement thereof, and means for connecting the respective lifting elements with a source of fluid supply, each connecting means having a valve arranged on one side of said actuating member and actuated by the movement thereof in one direction to control the flow of fluid to its lifting element and having a second valve arranged on the other side of said actuating member and actuated by the movement thereof in the other direction to control the flow of fluid from its lifting element to said source of supply.

3. In a multi-post lift comprising a plurality of fluid operated lifting elements and a load supporting structure carried by said lifting elements and capable of tilting movement with relation thereto, a main conduit connected with a source

of supply of fluid under pressure, means for delivering fluid from said main conduit to each lifting element to elevate said load supporting structure and for returning fluid from each lifting element to said main conduit to lower said load supporting structure, and means controlled by the tilting movement of said load supporting structure in one direction to restrict the supply of fluid to one of said lifting elements while said structure is being elevated and to restrict the return of fluid from another of said lifting elements to said main conduit while said structure is being lowered.

4. In a multi-post lift comprising a plurality of fluid operated lifting elements and a load supporting structure carried by said lifting elements and capable of tilting movement with relation thereto, a main conduit connected with a source of supply of fluid under pressure, a supply conduit and a return conduit connecting each lifting element with said main conduit, valves in said supply conduits and said return conduits, and means actuated by the tilting of said load supporting structure in one direction to actuate the valves in the supply conduit of one lifting element and in the return conduit of another lifting element.

5. In a multi-post lift comprising a plurality of fluid operated lifting elements and a load supporting structure carried by said lifting elements and capable of tilting movement with relation thereto, a main conduit connected with a source of supply of fluid under pressure, a supply conduit and a return conduit connecting each lifting element with a main conduit, valves in said supply conduits and said return conduits, yieldable means to retain said valves normally in their open positions, and means actuated by the tilting of said load supporting structure in one direction to close the valves in the supply conduit of one lifting element and in the return conduit of another lifting element while the valves in the other conduits remain open.

6. In a multi-post lift, a plurality of fluid operated lifting elements, a load supporting structure carried by said lifting elements and capable of tilting movement with relation thereto, an actuating member connected with said load supporting structure and operable by the tilting movement thereof, conduits connected with the respective lifting elements, each conduit comprising a branch to supply fluid to its lifting element and a second branch to exhaust the fluid from its lifting element, and two pairs of valves mounted on opposite sides of said actuating member for operation thereby, one valve of each pair being arranged in the supply branch of the conduit connected with one of said lifting elements and the other valve of that pair being arranged in the exhaust branch of the conduit connected with the other lifting element.

7. In a multi-post lift, a plurality of fluid operated lifting elements, a load supporting structure carried by said lifting elements and capable of tilting movement with relation thereto, an actuating member connected with said load supporting structure and operable by the tilting movement thereof, a main conduit connected with a source of fluid supply, two pairs of branch conduits to connect said main conduit with the respective lifting elements, each pair comprising a supply branch and an exhaust branch, check valves in the respective branch conduits to prevent the simultaneous flow of fluid through the two branches of either pair, controlling valves in the

respective branch conduits, means to hold said controlling valves normally in their open positions, and means actuated by said actuating member to move said controlling valves toward their closed positions, said controlling valves and the means for moving the same being so arranged with relation to said actuating member that the movement of said actuating member in one direction will operate the valve in the supply branch leading to one lifting element and the valve in the exhaust branch leading to another lifting element, and the movement of said actuating member in the other direction will operate the valve in the supply branch leading to the last mentioned lifting element and the valve in the exhaust branch leading to the first mentioned lifting element.

8. In a multi-post lift, fluid operated lifting elements near the respective ends of said lift, a load supporting structure carried by said lifting elements and capable of tilting movement, conduits leading to the respective lifting elements, a main conduit connected with a source of fluid supply, two valve casings each having a supply valve chamber and an exhaust valve chamber and having passageways connecting both valve chambers of the respective valve casings with said main conduit and connecting said supply valve chambers with the conduits leading to the respective lifting elements, and other passageways connecting the exhaust valve chamber of each casing with the conduit leading from the supply valve chamber of the other casing to the corresponding lifting element, a valve in each valve chamber, and means controlled by the tilting movement of said load supporting structure to selectively actuate said valves.

9. In a multi-post lift, lifting elements arranged near the respective ends of said lift and each comprising a vertical cylinder sunk in the ground and a ram mounted for longitudinal movement in said cylinder, a load supporting structure mounted on said rams for tilting movement with relation thereto, a downwardly extending rod rigidly secured to said load supporting structure, conduits connecting the respective cylinders with a source of fluid supply, each conduit comprising a branch to supply fluid to its cylinder and a second branch to return fluid from its cylinder to said source of supply, means for preventing the simultaneous flow of fluid through both branches of either conduit, a valve in each branch of each conduit, and actuating devices for said valves so arranged with relation to said rod that the tilting of said rod in one direction will cause the same to operate the valve in the supply branch of one conduit and the valve in the exhaust branch of the other conduit, and the tilting of said rod in the other direction will cause the same to operate the valve in the supply branch of the last mentioned conduit and the valve in the exhaust branch of the first mentioned conduit.

10. In a multi-post lift, fluid operated lifting elements near the respective ends of said lift, parallel rails supported by said lifting elements and having longitudinal channels, plates rigidly mounted in said channels adjacent to one of said lifting elements and having bearings, plates slidably mounted in said channels adjacent to the other lifting element and having bearings, cross members secured to the respective lifting elements and having parts mounted in the bearings of the respective plates, a downwardly extending actuating member connected with said rails and movable by the tilting of said rails, conduits to connect the respective lifting elements with a source of

fluid supply, valves in the respective conduits, and actuating devices for said valves so arranged with relation to said actuating member that the movement imparted to said actuating member by the tilting of said load supporting structure in one direction will operate a valve in one of said con-

duits and movement imparted to said actuating member by the tilting of said load supporting structure in the other direction will operate a valve in the other of said conduits.

ION VON KERT HOTT.
